RELEASABLE JARRING TOOL

Erwin Burns, Los Angeles, and Harry P. Wicker-
sham, Huntington Park, Calif.

Application August 7, 1933, Serial No. 684,020

13 Claims. (Cl. 255—27)

This invention relates to a well tool, and relates more particularly to a releasable jarring tool or jar. It is a general object of the present invention to provide a simple, practical and effective device for use in a string of drill pipe that is operable to impart a jarring action to a tool carried by the string and that is releasable to permit disconnection of the string from the tool.

In the drilling of wells with the rotary method of drilling, the drilling tool has a decided tendency to become caught in the well bore when penetrating certain earth formations. Jarring tools for imparting a hammering or jarring action to the drilling tool have been found effective in loosening the caught tools so that drilling may be continued. The jarring tools that have been introduced are very expensive, and it is not commercially practical to employ them in drilling strings. Further, the common forms of jarring tools are not releasable or capable of being disconnected when in the well and may be lost or damaged if employed in a drilling string in the event that the drilling tool cannot be loosened from the formation.

An object of the present invention is to provide a device adapted to be inserted in a drilling or fishing string that may be operated to impart a hammering or jarring action to the tool operated by the string and that may be released or disconnected, in the event the tool cannot be operated or loosened, to permit the major portion of the string to be recovered from the well.

Another object of the invention is to provide a releasable jarring tool of the character mentioned that is operable by a simple rotation of the operating string while maintaining the string under tension to provide any required number of jarring or hammering blows.

It is another object of the invention to provide a releasable jarring tool that is operable to dependably unyieldingly transmit heavy rotational and longitudinal strains during the normal drilling operations without becoming jammed or rendered inoperative.

It is another object of the invention to provide a releasable jarring tool that forms a rigid effective connection in the drilling string during the drilling operation and that may be easily reset to its normal condition after being actuated as a jarring tool.

It is another object of the invention to provide a releasable jarring tool that may be easily and quickly released or disconnected without being operated as a jarring tool or after being actuated to produce a jarring action.

It is another object of the invention to provide a releasable jarring tool that may be easily and quickly disconnected or released without special or difficult manipulation of the drilling string.

It is a further object of the invention to provide a releasable jarring tool that is effective in operation and simple and inexpensive of manufacture.

Other objects and features of the invention will be better and fully understood from the following detailed description of a typical form and application of the invention, throughout which description reference is had to the accompanying drawings, in which:

Fig. 1 is a side elevation of the tool provided by the present invention illustrating it connected in a drilling string. Fig. 2 is an enlarged longitudinal detailed sectional view of the tool with the stem section in elevation showing the parts in the locked or normal positions. Fig. 3 is an enlarged fragmentary longitudinal sectional view of the upper portion of the tool with the stem section in elevation showing the lock member in the up position. Fig. 4 is a fragmentary side elevation taken as indicated by line 4—4 on Fig. 3 illustrating the lugs in the position for disconnection. Fig. 5 is an enlarged longitudinal detailed sectional view of the tool with the stem section in elevation showing the parts in the jarred or jarring positions. Fig. 6 is an enlarged transverse detailed sectional view taken substantially as indicated by lines 6—6 on Fig. 2. Figs. 7 and 8 are enlarged transverse detailed sectional views taken as indicated by lines 7—7 and 8—8 respectively on Fig. 5.

The releasable jarring tool provided by the invention includes generally, two body sections A and B, releasable means 10 for transmitting strains between the body sections A and B, and means 11 operable to effect a jarring action 40 between the sections A and B after the release of the means 10.

The body sections A and B of the tool constitute an assembly adapted to be connected or interposed in a drilling string of drill pipe, or the like. 45 In the particular case illustrated in the drawings, the section A is connected with the string or the major portion S of the string, while the section B is connected with a drill collar C carrying the drilling tool T. The upper section A is the male 50 or stem section of the tool, while the lower section B is the female or socket section receiving the section A. The stem section A is comparatively long and is round in cross sectional configuration. A sub 12 may be provided on the upper end of the 55

section A to facilitate connection of the section with the string S. In the particular embodiment of the invention being described, the upper end portion of the stem section A is threaded into a 5 socket 13 in the lower end of the sub 12. A tapered socket 14 is provided in the upper end of the sub 12 to receive the threaded pin of a tool joint section, or the like, on the lower end of the string S. The stem section A is provided 10 with a central longitudinal fluid passage 15 extending through it from one end to the other. The upper end of the passage 15 is in communication with the passage 16 in the sub 12. The section B is a tubular member having a central 15 longitudinal opening 17 for receiving the stem section A. The lower portion 17a of the opening 17 is of enlarged diameter and its upper end forms a downwardly facing shoulder 18 in the section B. A sub 19 is screw threaded into the 20 lower end of the section B to facilitate connection of the section with the drill collar C or other part. The sub 19 may have a pin 20 for threading into a socket in the drill collar C. An opening or socket 21 is provided in the upper end portion 25 of the sub 19 and forms a continuation of the enlarged portion 17a of the opening in the section B. A fluid passage 22 is provided in the sub 19 in longitudinal alignment with the fluid passage 15 of the section A.

30 The releasable means 10 is operable to transmit rotational and longitudinal strains between the sections during drilling and other operations. The means 10 is releasable to condition the jarring means 11 and to permit the disconnection 35 of the body sections A and B. In accordance with the invention, the means 10 includes a releasable threaded connection between the body sections A and B, and a lock section or member 26 surrounding the section A and adapted to cooperate with the section B. The threaded connection comprises a comparatively short continuous thread 23 on the section A for cooperating with a broken thread 24 on the walls of the opening 17 in the section B. The thread 24 is broken at 40 diametrically opposite points to comprise two longitudinal series of spaced inclined shoulders for the purpose to be subsequently described. The threads 23 and 24 are preferably right hand threads being releasable by counter-clock wise or 45 left hand rotation of the body section A relative to the section B. There is preferably considerable clearance in the threads 23 and 24 when they are in mesh or cooperation to allow limited relative longitudinal movement between the sections A and B.

50 The lock section or member 26 is carried by the stem section A and is adapted to have releasable meshing engagement with the socket section B. The member 26 surrounds the stem section A between the lower end of the sub 12 and the upper end of the section B. In the construction illustrated in the drawings, the member 26 is tubular and is of substantially the same external diameter as the sub 12 and section B. Circumferentially spaced lugs 27 are provided on the lower end of the member 26 to cooperate with complementary lugs 28 projecting from the upper end of the socket section B. The ends of the lugs 27 and 28 are inclined and have the same pitch and 55 direction of inclination as the threads 23 and 24. The bottom walls 29 of the spaces or notches between the respective lugs 27 and 28 have the same pitch or inclination as the ends of the lugs. The sides of the lugs 27 and 28 are flat and are preferably convergent toward the ends of the lugs. The

60 lugs 27 and 28 are related and proportioned so that they are adapted to mesh to have their sides in engagement as illustrated in Fig. 1 of the drawings so as to effectively transmit rotational and compression strains between the member 26 and section B. 65

Means is provided for feeding the lock member 26 longitudinally on the stem section A upon rotation of the stem section A relative to the socket section B. Coarse threads 30 are provided on the stem section A and the interior of the member 26 to cause longitudinal movement of the member on the section A. The threads 30 are preferably double threads and have a steep or substantial pitch. In accordance with the invention, the threads 30 are left hand threads being pitched in the opposite direction to the threads 23 and 24. Upon the section A being turned in a right hand direction relative to the section B, the engagement of the forward ends 20 of the lugs 27 with the rear ends of the lugs 28 holds the member 26 against rotation so that the cooperation of the threads 30 feeds the member 26 downwardly bringing the lugs 27 into effective mesh with the lugs 28. It will be apparent that 25 when the member 26 is in this position where a right hand rotational strain is on the joint, it positively limits threading together of the sections. The member 26 thus prevents the threads 23 and 24 from being jammed so that they may 30 be easily disconnected without endangering the other threaded connections in the string. Upon the stem section A being turned in a left hand direction relative to the socket section B, the meshing lugs 27 and 28 hold the member 26 35 against rotation so that the threads 30 feed the member upwardly to the position illustrated in Fig. 4 of the drawings.

40 The invention includes means for normally yieldingly holding the lock member 26 in its up position where the lugs 27 are free to clear the lugs 28 upon turning of the section A in a left hand direction relative to the section B and for aiding in automatically returning the member 26 45 from its meshing position to its up position. A socket 31 is provided in the upper end of the lock member 26 and a helical torsional spring 32 is arranged in the socket and surrounds the section A. A ring 33 is arranged in the socket 31 and is held against turning in a counterclockwise direction by pins 34 engaging the upper ends of the threads 30 of the section A. The lower end of the spring 32 is held in a socket 35 in the ring 33. A plate ring 36 is attached to the upper end of the lock member 26 by screws 37, or the like and overhangs or closes the upper end of the socket 31. The upper end of the spring 32 is carried in a socket 38 in the plate ring 33. The ring 32 is held under a torsional strain and a compression strain to exert a right hand turning force and an up strain on the lock member 26 to normally yieldingly hold the lock member in its up position illustrated in Figs. 3 and 4 of the drawings and to aid in returning the lock member to this up position when the section A is turned in a 50 counterclockwise direction. The upward movement of the lock member 26 is limited by the lower end of the sub 12 which is engaged by the plate ring 36 when the lock member 26 is in its up position. When the lock member 26 is in this 55 position, the stem section A may be turned in a counterclockwise direction to unthread the threads 23 and 24 and condition the jarring means 11 for operation or provide for the dis- 75

connection of the sections A and B as will be subsequently described.

The means 11 for effecting a jarring action between the body sections A and B is rendered operative or conditioned for operation after the release of the means 10. The jarring means 11 includes an impact nut 40 on the lower end portion of the stem section A operable longitudinally in the enlarged opening 17^a and adapted to jar upwardly against the shoulder 18. The nut 40 is releasably connected with the stem section A by threads 41 having the same pitch and direction of inclination as the threads 23 and 24. Means is provided to control the release or detachment of the nut 40 from the stem section A. A spring pressed ratchet or latch 42 is carried by the nut 40 and is adapted to cooperate with a longitudinal groove 42^a in the wall of the opening 17^a to hold the nut 40 against rotation relative to the section B. The latch 42 is arranged in a socket 43 in the impact nut 40 and is urged outwardly by a spring 44. The active outer end 45 of the latch 42 projects through and is slidably guided by a perforated plug 46 in the socket 43. The active outer end 45 of the latch 42 is bevelled rearwardly and outwardly relative to the clockwise direction of rotation, so that it is adapted to ratchet or slip over the groove 42^a when the nut 50 is being turned in a right hand direction. When the nut 40 is turned in a counterclockwise direction, the active end 45 of the latch 42 is urged outwardly into the groove 42^a by the spring 44 and holds the nut 40 against further rotation in that direction. The latch 42 and the groove 42^a are positioned and related so that they are adapted to cooperate when the impact nut is in its up position where its upper end is at or adjacent the shoulder 18.

The means 11 for effecting a jarring or hammering action between the sections A and B includes parts on the sections adapted to cooperate to hold the sections against relative longitudinal movement that are releasable to allow the impact nut 40 to jar upwardly against the shoulder 18. The means 11 includes sets or series of inclined shoulders 50 on the stem section A for cooperating with sets or series of inclined shoulders 51 on the wall of the opening 17. In the preferred construction, there are two diametrically opposite sets of longitudinally spaced shoulders 50 on the section A for cooperating with two diametrically opposite series of longitudinally spaced shoulders 51 on the section B. The sets of shoulders 50 and 51 are proportioned and related so that the shoulders of the section A are adapted to pass between the sets of shoulders on the section B when the sections are in certain rotative positions. The shoulders 50 and 51 are inclined in the same direction as the threads 23 and 24 and have the same pitch as the threads 23 and 24. In practice the sets of shoulders 51 are aligned with the sets of parts or shoulders forming the interrupted thread 24. When the shoulders 50 and 51 are in mesh, they are operable to hold the sections A against longitudinal or upward movement relative to the section B. In accordance with the invention there is considerable clearance in the meshing series of shoulders 50 and 51 as clearly illustrated in Fig. 3 of the drawings. The leading ends 55 of the shoulders 50 are bevelled to insure their easy engagement with the shoulders 51. To effect a jarring action, after the release of the lugs 27 and 28, the stem section A is turned in a left hand or counter clockwise direction for about two revolutions to disen-

gage the continuous thread 23 from the broken thread 24, and is then rotated in a right hand direction while maintaining an up-pull on the string S and section A. The sets of shoulders 50 of the section A are adapted to pass between the sets of shoulders 51 once during each rotation of the stem section A in a right hand direction to permit the impact nut 40 to jar upwardly against the shoulder 18. After each jarring blow, the right hand rotation of the stem section A relative to the socket section B brings the shoulders 50 into cooperation with the shoulders 51, which feeds the section A downwardly relative to the section B moving the impact nut downwardly away from the shoulder 18 preparatory to the succeeding jarring blow.

During the normal drilling operation or when the string S is being turned in a clock wise or right hand direction or is under a clock wise rotational strain, the cooperation of the threads 30 holds the lock member 26 in its down position where the lugs 27 and 28 are in full or operative meshing engagement. The threaded feeding connection of the lock member 26 with the stem section A and the meshing engagement of the lugs 27 and 28 limits threading together of the sections A and B so that the threads 23 and 24 are relieved of tightening and wedging action. The safety joint thus forms a rigid unyielding joint or connection in the string during normal or drilling operations. If it becomes desirable or necessary to impart a jarring or hammering action to the tool T, the drilling string may be raised slightly or put under a slight up strain and is turned in a counterclockwise direction for approximately two revolutions to unthread the thread 23 from the thread 24. The cooperation of the threads 23 and 24 raises the section A to a position where the lugs 27 are free to clear the lugs 28. During the disconnection of the thread 23 from the thread 24, the nut 40 is in a position within the socket 21 where its latch 42 is spaced below the groove 42^a so that it is free to turn with the stem section A. Upon disconnection of the thread 23 from the thread 24 the stem section A 45 is permitted to shift upwardly a limited amount to bring the nut 40 to a position at or in cooperation with the shoulder 18. The string S is then rotated in a right hand direction while maintaining an up-pull, thus turning the section A in the right hand direction relative to the section B to cause the disengagement of the sets of shoulders 50 from the sets of shoulders 51 during each rotation. During the cooperation of the shoulders 50 with the shoulders 51, the section A feeds or is threaded downwardly relative to the section B to move the nut 40 downwardly away from the shoulder 18. The disengagement of the shoulders 50 from the shoulders 51 allows sudden upward movement of the section A relative to the section B to bring the impact nut 40 into upward jarring engagement with the shoulder 18, thus imparting an upward hammering or jarring action to the tool T. After the jarring action has taken place, the continued clock-wise rotation of the section A results in the shoulders 50 again meshing with the shoulders 51 whereby the stem section A is again fed downwardly to space the nut 40 below the shoulder 18 preparatory to the next jarring blow. In this manner the tool may be operated to provide any desired or required number of upward jarring or hammering blows to the tool connected with the section B.

In the event that the tool T becomes loosened by the jarring or hammering action, the string S 75

- is allowed to settle to take up the clearance in the shoulders 58 and 51 and is then rotated in a right hand or clock wise direction to cause feeding of the section A into the section B by threading together of the threads 23 and 24. When the section A assumes a position where the lugs 27 strike against the lugs 28 the string S may be raised and turned approximately one half of a revolution in a right hand direction and then permitted to settle, bringing the parts to the position where the lugs 27 and 28 are in full mesh. The drilling operation may then be continued as the member 26 is maintained in its meshing position by the cooperation of the feeding threads 28.
- 15 In the event that the jarring action to which the tool is subjected does not result in loosening of the tool from the formation, the joint may be disconnected without returning its parts to the normal position by merely rotating the string in the left hand direction while maintaining an up-strain on the string. The latch 42 cooperates with the groove 42^a during this left hand rotation of the section A so that the nut 48 is held against turning allowing the section A to be threaded out of the nut. Upon the shoulders 58 of the section A being unthreaded from the shoulders 51 and the thread 24 of the section B, the two sections of the joint are entirely disconnected and the string S may be recovered from the well.
- 20 To release or disconnect the section A from the section B when the parts are in the normal positions, the string S is rotated in a left hand or counterclockwise direction. The lugs 27 clear the upper ends of the lugs 28 during this rotation of the section A in a counterclockwise direction. The turning of the section A in a left hand or counterclockwise direction relative to the section B unthreads or releases the thread 23 from the thread 24 and permits the latch 42 to come into latching cooperation with the groove 42^a. The nut 48 is thus held against turning so that the stem section A may be threaded out of the nut. The inclined shoulders 58 of the section A are threaded up through the shoulders 51 and the thread 24 of the section B during the threading of the section A out of the nut 48 and when the section A is released from the nut it is fully disconnected from the section B. The operating string may then be recovered from the well.
- 25 Having described only a typical form and application of our invention, we do not wish to be limited or restricted to the specific form and application herein set forth, but wish to reserve to ourselves any modifications or variations that may appear to those skilled in the art or fall within the scope of the following claims:
- 30 Having described our invention, we claim:
1. A well tool including, two sections adapted to be connected in an operating string, releasable means for transmitting strains between the sections including a sleeve around and movable on one section, and threads on said section and sleeve for feeding the sleeve into and out of strain transmitting cooperation with the other section, and means operable to effect a jarring action between the sections after the release of the first mentioned means.
- 35 2. A tool for use in an operating string including, two sections, a slack threaded connection between the sections releasable by manipulation of the string while in the well, clutch parts on one section, a sleeve threaded on the other section and releasably cooperating with the clutch parts for transmitting strains between the sections to prevent tightening of the threads of said con-

nection, and means for effecting a jarring action after the release of said connection, including an impact part on one section slackly linking the sections together and detachable from said section by manipulation of the string to allow disconnection of the sections after the release of said connection.

3. A tool for use in an operating string including, two sections adapted to be connected in the string, releasable means for transmitting rotational and compression strains between the sections, impact parts on the sections adapted to be brought into hammering engagement upon relative longitudinal movement between the section, means for holding the sections against relative longitudinal movement after the release of the first mentioned means and releasable to allow the impact parts to be brought into engagement, and means connecting one of said impact parts with its respective section to be disconnectable therefrom after the release of the first mentioned means.

4. In combination, an operating string, a drilling tool on the lower end of the string, and a device in the string including two sections, impact parts on the sections adapted to be brought into jarring engagement, inclined parts on the sections adapted to cooperate to hold the sections against relative longitudinal movement releasable by relative rotation between the sections to allow said parts to come into engagement, means operable to normally transmit rotative and longitudinal strains between the sections releasable to allow relative movement of the sections, and a connection between one of the impact parts and its respective section releasable to allow disconnection of the sections.

5. A well tool including, two sections related for relative rotation and longitudinal movement, cooperating releasable threads on the sections, impact parts on the sections adapted to be brought into jarring engagement upon relative longitudinal movement of the sections, inclined shoulders on the sections adapted to cooperate to hold the sections against relative longitudinal movement releasable by relative rotation between the sections one of said parts being disconnectable from its respective section upon relative rotation between the sections in one direction while in the well to permit the disconnection of the sections, the shoulder of one section threading through the thread of the other section during said disconnection, and releasable means for holding the sections against relative rotation.

6. A well tool including, two sections adapted to be connected in an operating string, a shiftable member on one section, lugs on the member and the other section adapted to have non-rotative cooperation, and a connection between the member and the first mentioned section operable to feed the member toward said other section upon rotation of the first mentioned section in one direction to bring the lugs into cooperation to hold the sections against rotation and operable to retract the member from the said other section upon rotation of the first mentioned section in the other direction to release the lugs, and means operative after release of the lugs for effecting a jarring action between the sections, the sections being detachable one from the other after the release of the lugs.

7. A well tool including, two sections adapted to be connected in an operating string, releasable

lug and notch means holding the sections against relative rotation, and means operative after release of the first mentioned means for effecting a jarring action between the sections, the sections being detachable one from the other after the release of the first mentioned means, the last mentioned means including impact parts on the sections adapted to come into jarring engagement upon longitudinal movement of one section relative to the other, one of said impact parts being detachable from the section carrying it upon rotation of said section relative to the other section.

8. A tool for use in a string of pipe operating in a well including two sections to be connected in the string, threads connecting the sections, a lock member threaded on one section, lugs on the lock member and the other section adapted to cooperate when the string is under a torsional strain tending to tighten the threads, the member automatically retracting to disengage the lugs when a reverse rotational strain is on the string, and means for effecting a jarring action between the sections when the threads are disengaged.

9. A tool for use in a string of pipe operating in a well including two sections to be connected in the string, threads connecting the sections, a lock member threaded on one section, lugs on the lock member and the other section adapted to cooperate when the string is under a torsional strain tending to tighten the threads, the member automatically retracting to disengage the lugs when a reverse rotational strain is on the string, and means for effecting a jarring action between the sections when the threads are disengaged, said means including an impact part, and threads connecting the impact part to said section whereby said part is adapted to be unthreaded by rotation of the string to allow the separation of the sections.

10. A safety joint including, a socket section, a stem section releasably threaded into the socket section, a shiftable member on the stem section, parts on the member and socket section adapted to have releasable non-rotative cooperation, threads connecting the member with the stem section and pitched in the opposite direction to the threads connecting the sections to advance the member on the stem section to bring said parts into cooperation when the stem section is turned in a direction to thread the sections together and to retract the member when the sections are under torque applied in the other direction, and a spring surrounding the stem section

and connected to the stem section and member to urge the member to the retracted position.

11. A safety joint including, two sections one a stem section, the other a socket section receiving the stem section, a releasable threaded connection between the sections, a member on the stem section adapted to engage the socket section, threads connecting the member with the stem section and pitched in the opposite direction to the threads of said connection to maintain the member in engagement with said other section when a clockwise strain is on the joint to limit threading together of the sections and operable to retract the member from said other section when a counterclockwise strain is on the tool to disengage the member from said other section, and a torsional spring surrounding the stem section and normally yieldingly holding the member in a retracted position.

12. A safety joint including, two sections, a releasable threaded connection between the sections, a member on one section adapted to engage the other section, threads connecting the member with the first mentioned section and pitched in the opposite direction to the threads of said connection to maintain the member in engagement with said other section when a clockwise strain is on the joint to limit threading together of the sections and operable to retract the member from said other section when a counterclockwise strain is on the tool to disengage the member from said other section, and a torsional spring surrounding the first-mentioned section and acting between the first mentioned section and the member to aid in the retraction of the member.

13. A safety joint including, two sections, a releasable threaded connection between the sections, a member on one section, parts on the member and the other section adapted to have releasable non-rotative cooperation, threads connecting the member with the first mentioned section and pitched in the opposite direction to the threads of said connection to hold said parts in cooperation with the sections are under torque applied in a direction to tighten the threads of said connection and to move the member relative to the sections to disengage said parts when the sections are stationary and under torque applied in the other direction, and a spring spaced longitudinally from said threads urging the member to a position where said parts are disengaged.

ERWIN BURNS.
HARRY P. WICKERSHAM. 55
